UNITED STATES PATENT OFFICE

163,638

PERFORATED STRIP

Jay Rosten, Brooklyn, N. Y.

Application March 10, 1949, Serial No. 1,322

Term of patent 14 years

(Cl. D54—2)

To all whom it may concern:

Be it known that Jay Rosten, a citizen of the United States of America, residing at Brooklyn, New York, in the county of Kings and State of New York, has invented a new, original, and ornamental Design for a Perforated Strip, of which the following is a specification; reference being had to the accompanying drawing, forming part thereof.

Figure 1 is a front view thereof.

Figure 2 is a side edge view thereof.

I claim:

The ornamental design for a perforated strip, as shown.

JAY ROSTEN.
